NURSING BOTTLE HOLDER

Laird C. Williams, Parkersburg, W. Va.

Application December 16, 1952, Serial No. 326,279

3 Claims. (Cl. 248—105)

1

This invention relates to nursing bottle holders and more particularly to a portable nursing bottle holder which may be set up for use at various locations and can be reduced to a compact condition for transportation or storage.

It is among the objects of the invention to provide an improved nursing bottle holder which is freely portable and can be set up for use in various locations as on an infant's bed or crib, an ordinary bed, a couch or a floor; which will hold a nursing bottle in position for use with the bottle inclined downwardly from its bottom end to its nipple carrying end; which resiliently supports the bottle and tends to hold the nipple end of the bottle a short distance above the mouth of an infant nursing from the bottle so that the nipple will be quickly withdrawn from the infant's mouth if the infant strangles and releases the nipple; which is readily adjustable to support the associated bottle at different heights and can be quickly folded to a compact condition for transportation or storage; and which is simple and durable in construction, economical to manufacture, easy to use and neat and attractive in appearance.

Other objects and advantages will become apparent from a consideration of the following description and the appended claims in conjunction with the accompanying drawing wherein:

Figure 1 is an end elevational view of the bottle holder with a nursing bottle supported by the holder in proper position for an infant nursing from the bottle;

Figure 2 is a top plan view of the holder and bottle illustrated in Figure 1;

Figure 3 is a side elevational view of the bottle holder;

Figure 4 is a fragmentary cross sectional view on an enlarged scale on the line 4—4 of Figure 1; and

Figure 5 is a perspective view of a cross bar constituting a component of the bottle holder.

With continued reference to the drawing, the holder comprises a pair of standards 10 and 11 of inverted T-shape, the cross members of which, as indicated at 12 for the standard 10, are longitudinally curved and concave at their edges remote from the stem portions, as indicated at 13, to provide spaced apart foot formations, as indicated at 14 and 15 located one at each end of the cross portion of the T-shaped standard. The foot formations 14 and 15 have their terminal surfaces in a common plane which is substantially perpendicular to the longitudinal center line of the associated stem portion 13 so that

2

the standards will stand with their stems in upright position when the foot portions thereof are resting on a substantially horizontal surface, such as the top surface of a bed or a floor.

The standards are held in spaced apart relationship to each other by a cross bar 16 of elongated, rectangular cross sectional shape pivotally connected at its respectively opposite ends to the standards 10 and 11.

Each standard is provided in the concave edge of its cross portion 12 remote from the stem portion 13 thereof with a rectangular notch 17 having a length and depth corresponding to the width and thickness of the cross bar 16 and a block 18 is secured to one side of the standard medially of the length of the cross portion 12 thereof and has an end portion 19 overlying and extending beyond the adjacent end of the notch 17 and provided with a transversely extending aperture disposed below the notch 17, outwardly of the side of the standard on which the block 18 is mounted and perpendicular to a plane which is perpendicular to the major surfaces of the standard and includes the longitudinal center line of the stem portion 13 of the standard. The block 18 on the standard 10 has a width less than the length of the corresponding notch 17 and is mounted symmetrically of the mid length location of the notch to provide spaces of equal width between the opposite ends of the notches and the adjacent sides of the downwardly extending portion 19 of the block for a purpose which will presently appear.

An abutment block 20 is mounted on the side of the standard 10 remote from the pivot block 18 and this block has an end surface at the upper or inner side of the notch 17 and substantially in a plane perpendicular to the longitudinal center line of the stem portion 13 of the standard.

The bar 16 is provided at one end with outwardly and downwardly extending, apertured lug formations 21 and 22 which are spaced apart to receive the lower portion 19 of the block 18 therebetween with their apertures in registry with the bore or aperture in the lower portion 19 of the block 18. The bar 16 has one end thereof disposed in the notch 17 with the lug formations 21 and 22 on this end of the bar disposed at the respectively opposite sides of the lower portion of the block 18 and a pivot pin 23 extends through the registering apertures in the lugs 21 and 22 and the block 18 and pivotally connects the corresponding end of the bar 16 to the standard 10.

The standard 11 is provided in its cross portion

with a notch similar to the notch 17 and is provided on one side with a pivot block 24 similar in all respects to the pivot block 18 and extending downwardly past the adjacent side of the corresponding notch. This standard is also provided at its side remote from the pivot block 24 with an abutment block 25, the lower end surface of which is disposed at the upper or inner side of the corresponding notch in the standard and substantially in a plane perpendicular to the longitudinal center line of the stem portion of this standard.

The bar 16 has on its end remote from the lugs 21 and 22 similar lugs 26 and 27 which are spaced apart to receive the lower portion of the pivot block 24 therebetween and a pivot pin 28 extends through the registering apertures in the pivot block 24 and in the lugs 26 and 27 on the bar 16 to pivotally connect the standard 11 to the corresponding end of the cross bar 16.

When the standards are pivotally assembled with the cross bar, as illustrated in Figure 3, the pivot blocks 18 and 24 are disposed at the outer sides of the standards and the abutment blocks 20 and 25 are disposed at the inner sides of the standards and rest at their bottom ends on the upper surface of the cross bar 16 adjacent the corresponding standards. The standards may be swung in the opposite direction about their pivotal connections with the corresponding ends of the cross bar 16 until they are disposed substantially against the lower side of the cross bar, to reduce the holder to a compact, folded condition for transportation and storage.

A hook 30 projects substantially perpendicularly from one side edge of the standard 10 near the end of this standard remote from the cross portion 12 of the standard and a hook plate 31 is pivotally mounted on the outer side of the standard 10 at one end, as indicated at 32, and has at its other end a hook formation projecting outwardly from the side edge of the stem portion of the standard remote from the hook 30, the hook plate 31 being disposed below the hook 30 but preferably above the mid length location of the stem portion 13 of the standard.

A hook 33 corresponding to the hook 30 projects substantially perpendicularly from the stem of the standard 11 near the upper end of the stem portion of this standard and a hook plate 34 similar to the hook plate 31 is pivotally secured at one end to the outer side of the standard 11, as indicated at 35, below the hook 33 and has a hook portion extending outwardly from the side edge of the stem portion of the standard 11 remote from the side edge from which the hook 33 extends. The hooks 30 and 33 extend from corresponding edges of the standard 11 and the hook plates 31 and 34 also extend from corresponding edges of the standard stems and opposite the hooks 30 and 33.

A doubled strand 36 of elastic material, such as rubber, is hooked at its ends over the hooks 30 and 33 and is provided intermediate its length with a bottle receiving loop 37 and a similar doubled strand 38 of elastic material is hooked at its ends over the hook portions of the hook plates 33 and 34 and is provided intermediate its length with a bottle receiving loop 39. The strand 38 is disposed below and substantially parallel to the strand 36 and the strands 36 and 38 are both disposed substantially parallel to the cross bar 16 of the holder, and, when unextended, are much shorter than the cross bar so that the standards are convergently inclined from the

cross bar to the ends of the standards near which the elastic strands are attached to the standards.

Adjusting screws 41 and 42 are threaded through the cross bar 16 near the inner sides of the standards 10 and 11 respectively and have knurled heads 43 and 44 respectively on their ends below the cross bar. At their upper ends these screws engage the bottom surfaces of the abutment plates 20 and 25 and, when threaded inwardly of the cross bar 16, tend to force the upper ends of the standards 10 and 11 away from each other and tension the elastic strands 36 and 38. At the same time these bend the cross bar 16 downwardly until the mid length portion of the cross bars is substantially in the plane of the lower ends of the standards.

When a nursing bottle 40 is mounted on the holder the bottle is slipped through the bottle receiving loops 37 and 39 with the loop 37 near the bottom end of the bottle and the loop 39 near the nipple receiving end of the bottle so that the bottle is held in a position downwardly inclined from its bottom end to its nipple receiving end for proper operation of the nipple.

The bottle is held a short distance above the mouth of an infant disposed below the strands 36 and 38 in position to nurse the bottle. The nipple can be forced downwardly and inserted into the infant's mouth and will be held by the infant while nursing from the bottle continues. If, however, the infant should strangle and release the nipple, the nipple will be immediately withdrawn from the infant's mouth so that the strangling will not be serious.

The bottle holder can be easily set up on any substantially horizontal surface and a pad of a suitable character placed over the cross bar 16 so that the infant may lie in position extending over this downwardly bent cross bar without discomfort. It will be noted that the cross bar is made wide and flat so that it can easily be padded to a comfortable condition. The nursing bottle is then properly adjusted, as explained above, and the infant may proceed to nurse from the bottle without assistance, usually until the bottle is emptied or the infant's hunger satisfied.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

60 1. A portable nursing bottle holder comprising standards each having spaced apart foot formations at one end thereof, a cross bar extending between and pivotally connected at its opposite ends to said standards, abutment means 65 acting between said bar and said standards, limiting pivotal movements of said standards in one direction relative to said bar to a position at which said standards are substantially parallel to each other, said standards being movable in the other direction relative to said bar to a position at which they are disposed substantially against one side of the bar, and strands of elastic material extending between said standards when the latter are in position substantially parallel to each other, said strands being spaced

apart transversely and longitudinally of said standards and provided intermediate their length with bottle receiving loops.

2. A portable nursing bottle holder comprising standards each having spaced apart foot formations at one end thereof, a bar extending between and pivotally connected at its opposite ends to said standards at which said foot formations are provided, abutment means acting between said bar and said standards limiting pivotal movement of said standards in one direction relative to said bar to a position at which said standards are substantially parallel to each other, hooks extending one from each standard at locations spaced apart longitudinally of the standards, and strands of elastic material secured at their ends to corresponding hooks on each standard and disposed substantially parallel to each other and to said cross bar and having bottle receiving loops intermediate their length for holding a nursing bottle between said standards and above said cross bar.

3. A portable nursing bottle holder comprising standards each having spaced apart foot formations at one end thereof, a bar extending between and pivotally connected at its opposite ends to said standards at which said foot formations are

provided, abutment means acting between said bar and said standards limiting pivotal movement of said standards in one direction relative to said bar to a position at which said standards are substantially parallel to each other, hooks extending one from each standard at locations spaced apart longitudinally of the standards, strands of elastic material secured at their ends to corresponding hooks on each standard and disposed substantially parallel to each other and to said cross bar and having bottle receiving loops intermediate their length for holding a nursing bottle between said standards and above said cross bar, and adjustable means carried by said bar and engaging said abutment means adjacent the pivotal connections between said standards and the corresponding ends of said bar for adjustably moving the ends of said standards remote from said cross bar away from each other.
